MILTON C. WHITAKER, OF NEW YORK, N. Y.

PROCESS OF DISTILLATION.

1,110,850.

Specification of Letters Patent. Patented Sept. 15, 1914.

Application filed November 12, 1912. Serial No. 730,934.

To all whom it may concern:

Be it known that I, MILTON C. WHITAKER, a citizen of the United States, residing at New York, in the county of New York, State of New York, have invented certain new and useful Improvements in Processes of Distillation, of which the following is a description, reference being had to the accompanying drawings, forming a part hereof.

- 10 My invention relates to the distillation of wood and other substances and particularly to what is termed destructive distillation, and has for its object to equalize the heat throughout the mass of material being treated so that all of the material treated will be brought to and maintained at the temperature desired for distilling off the more volatile substances present or for driving off the products resulting from the destructive distillation, and so that the temperature of all parts of the mass of material up at a uniform rate and thus prevent any one part of the mass from advancing in its distillation or decomposition faster than other parts.
- 15 20 25 30 By attaining these objects the time required for producing successive fractional distillates and for completing the destructive distillation is reduced and the yield of the more volatile and more valuable fractional distillates is increased.

With these objects in view, my invention consists in the process as hereinafter described and claimed of causing a circulation and mixing of heated gases within a retort containing a charge of non-liquid material in pieces or fragments to be subjected to distillation and heated by any usual means such as by direct fire heat, the circulation of a heating medium about the exterior of the retort or by circulation of a heating medium within the retort.

It has been found that where a retort is filled with wood and heated even by the circulation of a heating medium, by means of which a more equable heat throughout the retort can be maintained than can be done by fire heat applied directly to the retort, the temperature at different points in the charge varies sometimes as much as 100 degrees Fahrenheit, so that in order that the products, which are driven off at a particular temperature, may be driven off from all of the wood or other coal matter which form the charge, it is necessary to maintain the heat for a long time at a very considerable expense for fuel, as unless this is done some

part of the charge is not heated sufficiently to drive off the more volatile substances with the result that such substances remaining in the part of the charge not brought to the proper heat, are driven off with the less volatile and usually less valuable substances produced by the higher degree of heat subsequently applied as the treatment progresses toward the complete destructive distillation. And it has been found that proper, uniform and controlled temperature in the mass of the material treated increases the yield of the more valuable and more volatile products and presumably decreases the yield of the heavier, less volatile products which result from the heat in certain parts of the mass advancing so far as to crack and decompose the lighter products as they distil out, but heretofore it has been difficult to secure the uniformity of temperature throughout the mass even with effective control of the heat applied by reason of the fact that without the stirring of the gases the radiation from the walls of the retort must be depended on to penetrate the mass of material while by stirring the gases in accordance with my method convection currents are set up and the heat is rapidly distributed.

The drawing, which is illustrative of an apparatus adapted for use in carrying out my process and is not intended to limit the invention to the use of the particular apparatus shown or to the use of any particular apparatus, is a longitudinal section, partly diagrammatic of a wood distilling retort provided with means for carrying out the process of my invention.

In the drawing, 1 is a retort adapted to receive a charge of wood or other material to be subjected to distillation, the wood or other material forming the charge being preferably carried by cars 2 arranged to run on a track 3, the cars being preferably provided with end plates 4 of a height sufficient to offer material obstruction to the passage of the current of gases as hereinafter described, and thus serve as baffle plates.

5 indicates a dome into which the volatile products rise as the distillation proceeds, and from this dome a pipe 6 leads to a condenser 7.

8 indicates a furnace for heating the retort from which the products of combustion pass beneath the retort and are discharged through the stack 9. Other means for heating the retort may be used if desired.

At some convenient point in the retort I arrange a fan 10, here shown as arranged to be driven by a shaft 11 and pulley 12. To the intake of the fan casing is connected a pipe 13 preferably extending along the bottom of the retort and having its open end near the entrance end of the retort and to the discharge opening of the fan casing is connected a pipe 14 extending upward nearly to the top of the retort and bent near its upper end so as to discharge in a direction toward the entrance end of the retort.

In operation after the charge of the material to be subjected to distillation on the cars 2 or otherwise has been introduced into the retort and the retort closed as the retort begins to be heated the fan 10 is started drawing in the heated gases through the inlet pipe 13 and discharging them through the discharge pipe 14, thus maintaining a constant circulation thus drawing away highly heated gases from the hotter parts of the retort and distributing these hot gases to the cooler parts of the retort, displacing the cooler gases and forcing them toward the hotter parts of the retort, and at the same time causing the heated gases to circulate through the wood or other material of the charge. The end plates 4 serve to obstruct the flow of gases from the discharge pipe 14 to the mouth of the inlet pipe 13 and cause the gases to form eddies and to circulate throughout the material of the charge so as to cause the material at the center of the charge to be brought to the same temperature as the portions on the outside of the charge where they are more directly exposed to radiation from the walls of the retort. By regulating the heat applied to the retort and at the same time circulating the gases in the retort the entire charge may be brought to the temperature desired and maintained at such temperature so as to effect the driving off of all of the substance which is volatilizable at the particular temperature.

It will, of course be understood that the volatilized substances pass off in the form of vapor through the dome 5 and pipe 6 to the condenser 7, and it will be further understood that in the distillation of resinous wood to which the process is particularly applicable, the charge will be first brought

to a heat until substantially all of the turpentine is driven off, and the temperature will then be raised and maintained at successively higher temperature to drive off such fractional distillates as it may be found possible or desirable to produce, the heat being finally raised to the degree necessary to effect the destructive distillation of the wood.

It will, of course, be understood that instead of using the end plates 4 of the cars as baffle plates, other baffle plates may be used, or the baffle plates may be omitted.

The process requires for carrying it out only a fan with inlet and outlet arranged at a distance from each other, and such apparatus may be readily placed in position in any retort and will enable retorts which have been abandoned as inefficient or uneconomical to be operated at a profit.

Having thus described my invention, what I claim is:—

1. The herein described process of distillation which consists in so charging a retort with wood or other non-liquid material in fragments or pieces in a container that space for circulation of gases is left between the charge and the walls of the retort and the material is kept from contact with said walls, heating the retort, and equalizing the temperature throughout the charge by mechanically stirring the gases and vapors within the retort.

2. The herein described process of distillation which consists in so charging a retort with wood or other non-liquid material in fragments or pieces in a container that space for circulation of gases is left between the charge and the walls of the retort and the material is kept from contact with said walls, heating the retort, and equalizing the temperature throughout the charge by stirring the gases and vapors within the retort by withdrawing them from one part of the retort and returning them to another part thereof.

This specification signed and witnessed this twenty sixth day of October, A. D. 1912.

MILTON C. WHITAKER.
